GOLF PUTTING TARGET

James G. Porteus, Toledo, Ohio, assignor to Phillip A. Porteus

Filed July 26, 1965, Ser. No. 86,286

Term of patent 7 years

(Cl. D34—5)

FIG. 1

FIG. 2

FIG. 3

FIG.4

FIG.5

FIG.6

FIG.7

FIGURE 1 is an oblique front and top perspective view of a golf putting target showing my new design thereof;

I claim:

The ornamental design for a golf putting target, as shown.
